HERBERT B. TAYLOR, OF ROCNESTER, NEW YORK, ASSIGNOR TO GENERAL RAILWAY SIGNAL COMPANY, OF GATES, NEW YORK, A CORPORATION OF NEW YORK.

CONTACT-SHOE FOR AUTOMATIC TRAIN-CONTROL SYSTEMS.

1,308,535.

Specification of Letters Patent. Patented July 1, 1919.

Application filed September 21, 1915. Serial No. 51,791.

To all whom it may concern:

Be it known that I, HERBERT B. TAYLOR, a citizen of the United States, and a resident of the city of Rochester, in the county 5 of Monroe and State of New York, have invented a new and useful Contact-Shoe for Automatic Train-Control Systems, of which the following is a specification.

This invention relates to contact shoes for 10 automatic train control systems, and more particularly to contact shoes which are adapted to be secured to a railway vehicle and to coöperate with suitable contact rails or ramps located along the trackway for 15 said vehicle, and which, by their mechanical and electrical coöperation with said ramps, furnish the means for communicating the impulses or influences from the trackway to the moving vehicle necessary for the operation 20 of the train control system.

One of the principal objects of this invention is to devise a simple and durable contact shoe for automatic train control systems which will perform the dual function of a 25 collector of electrical energy and of a circuit controlling device.

A further object of the invention is to devise a simple and durable contact shoe for 30 automatic train control systems which will open and close different controlling circuits selectively according to the direction in which the vehicle carrying said shoe travels over the track.

A still further object of the invention is 35 to devise a simple and durable contact shoe for automatic train control systems, together with electrical appliances and electrical connections therefor, which will operate to nullify the circuit controlling function ordinarily performed by the shoe and which will cause a suitable signal to be operated on the vehicle whenever the vehicle proceeds over the trackway in the direction opposite to the normal direction of traffic.

40 Other advantages and objects will appear as the description of the invention progresses and the novel features of the invention will be particularly pointed out in the appended claims.

45 Generally stated, the invention consists in

a movable contact shoe which is suspended from a suitable support, carried on the train, by two parallel links, together with suitable controlling devices which are selectively operated when said contact shoe is moved 55 from its normal position in one direction or the other in the plane of said parallel links.

The invention further consists in the parts, and in the arrangements and combinations of parts, which are more fully set forth 60 hereinafter.

In describing the invention in detail, reference is had to the accompanying drawing, wherein I have illustrated a preferred physical embodiment of my invention, and where- 65 in like characters of reference designate corresponding parts throughout the several views, and in which:

Figure 1 is a view, which may be termed a front view, of a contact shoe embodying 70 the invention, the front cover plate for said shoe being removed, and certain parts of said shoe being shown in section substantially on the line 1—1 in Fig. 2, and other parts being partly broken away, in order to 75 more clearly show the construction of the different parts of said shoe; Fig. 2 is a vertical section of the shoe, taken substantially on the line 2—2 in Fig. 1, certain parts being partly broken away and other parts being 80 shown in elevation for the sake of clearness; Fig. 3 is an enlarged detail section on the line 3—3 in Fig. 1; and Fig. 4 is a diagrammatic view showing the electrical wiring and connections between the parts of the contact 85 shoe and certain devices of one form of a train control system with which the contact shoe can be used.

Referring to the accompanying drawing, the contact shoe is designed to be supported 90 in any suitable way (not shown), preferably adjustably, on some part of the vehicle or train, as on a journal box, an axle, a truck side frame or the like; and to attain this end, the contact shoe is mounted on a bar 5 of 95 wood or other insulating material which serves to insulate the whole shoe from the car. The shoe, as a whole, comprises a body portion or casting A which, in effect, consists of two box-like chambers or casings B 100

and C arranged one above the other. The body portion A of the shoe is secured to the bar 5 by two bolts 6, a plate or washer 7 being interposed between the nuts of said bolts and the bar 5. The shoe proper comprises a block 8 in which is revolvably mounted a disk-like foot 9, which is the portion of the shoe which actually contacts with the ramp; and said foot 9 is formed with an 10 standing bearing stud 10 which is journaled in the block 8 and which is held in place therein by two pins 11 engaging a circumferential groove 12 in said bearing stud 10. The block 8 is supported by two parallel 15 crank arms pivoted at one end to the body portion A of the shoe and at the other end to the block 8; and since the construction of the crank arms 13 and their associated parts connected thereto and operated thereby are 20 constructed the same, a description of one will suffice for both, and the corresponding parts will be designated by the same reference characters, with the distinctive exponent 1 added thereto.

25 Each of the crank arms 13 has a laterally projecting bearing stud 14 at its lower end which extends through a corresponding hole in the block 8, a washer 15 and a cotter pin 16 serving to hold said block in place on said 30 stud. The shaft 17 which is secured to or integral with the upper end of each crank arm 13 is journaled in the front and back walls of the lower casing B, a collar 18 fastened to said shaft 17 by a pin 19 serving to 35 hold it in place. Mounted loosely on the shaft 17 adjacent to the front wall of the lower casing B is a collar 20 having several teeth 21 formed along its upper edge and a downwardly projected stop 22. Next to the 40 collar 20 is another collar 23, which performs the function of actuating the collar 20 and will be hereinafter termed the driver. The driver 23 fits tightly on a squared portion of the shaft 17 so as to turn therewith 45 and has projecting from its lower edge a finger 24 which is arranged to engage the stop 22 of the corresponding loose collar 20. as shown in the Fig. 1 of the drawing, the fingers 24 and 24¹ of the drivers 23 and 23¹ are 50 located on opposite sides of the stops 22 and 22¹ of the loose collars 20 and 20¹ for the purpose which will be made clear herein- 55 after in a description of the operation. A sleeve 25 surrounds the shaft 17 and bears at one end against the driver 23 and at its other end against the inside face of the rear wall of the lower casing B.

Integral with or secured to the back wall of the lower casing B are two pivot studs 26 60 which are arranged one above each of the shafts 17; and on each pivot stud 26 is journaled a lever 27, held in place by a washer 28 and a cotter pin 29. The levers 27 and 27¹ are counterparts; and each have at its 65 lower end a number of teeth 30 meshing with

the teeth 21 of the corresponding loose collar 20. Each lever 27 is formed with an integral conical cup 31, the open end of which is opposite to the other lever; and arranged between the two levers 27 and 27¹ 70 are two telescoping rods 32 and 33 which have hemispherical heads 34 bearing against the bottoms of the cups 31 and 31¹ and which are surrounded by a compression spring 35 bearing against the heads 34 and 75 tending to press the lower ends of the levers 27 and 27¹ apart. The greater part of the length of each rod 32 and 33 is divided into four strips which are substantially sector- 80 shape in cross section and which are arranged at right angles to each other, as shown to the best advantage in Fig. 3; and the respective strips of the two rods 32 and 33 overlap and permit a telescopic movement of said rods. The outer edges of the levers 85 27 are formed with flat faces or seats 36 which normally bear against the side walls of the lower casing B.

The upper ends of the levers 27 and 27¹ 90 extend upwardly through a slot 37 in the bottom of the upper casing C and have integral therewith or secured thereto laterally extending pins 38 and 38¹. In the upper casing C are two contact drums D and D¹, each comprising a shaft 39 journaled in 95 bosses 40 integral with the end walls of the upper casing C, and sleeves or drums 41 of suitable insulating material secured to said shaft 39. To the contact drums D and D¹ are pinned crank arms 42 and 42¹, the lower 100 ends of which are split and straddle the pins 38 or 38¹ in the corresponding lever 27 or 27¹. Suitable contact bars or segments 43 are fastened to the insulating sleeves 41 and 41¹, the functions and arrangement of these contact bars being more 105 fully set forth hereinafter in a description of the operation. Between the contact drums D and D¹ are two contact supporting blocks 44 of insulating material which 110 are fastened by screws 45 to bosses 46 integral with the bottom of the upper casing C. Suitable contact springs 47 are fastened to these contact supporting blocks 44 by bolts 48 having the usual washers and lock nuts 115 associated therewith adapted to form binding posts for the convenient attachment of wires. The contact springs 47 are preferably clamped to the under side of the contact supporting blocks 44, as shown in Fig. 1, 120 these contact springs 47 extending upwardly and having V-shaped humps extending toward the corresponding contact drum D, the upper ends of said contact springs 47 having 125 downwardly projecting hooks which engage counterpart hooked stop members 49 clamped by the bolts 48 to the upper faces of said insulating blocks 44.

The upper casing C is provided with the suitable cover 50 which is preferably se- 130

cured to said casing by the hinge 51 at one edge and by a clamping hasp or catch 52 at its other end. The upper part of the outer or front wall of the lower chamber B is 5 preferably open so as to permit easy access to the parts of the contact shoe located in said lower casing; and a suitable cover plate 53 is fastened by cap screws 54 over this opening. The electric conductors connected 10 to the contact springs 47 are not shown in the drawing in order to avoid confusion, but it is to be understood that these conductors are disposed in the space between the two contact supporting blocks 44 and are preferably formed into a cable 55 passing through one wall of the upper casing C and through 15 a suitable fitting 56 (see Fig. 2), from whence the cable extends to the body of the vehicle on which the contact shoe is supported and to such suitable apparatus carried by said vehicle as is controlled by said shoe.

In order to make the operation of the shoe shown and hereinafter described clear, 20 the parts of the shoe are illustrated diagrammatically in Fig. 4 in connection with a certain arrangement of automatic train control devices and controlling circuits therefor with which the shoe can be satisfactorily operated; but it is to be understood that the application of the shoe to the particular train control system shown is merely for 25 illustrative purposes, since these form no part of my invention, and that the shoe may be used with other train control systems having different devices and different controlling circuits. Referring to Fig. 4, one track rail for the vehicle is designated by the numeral 60 and one wheel of the vehicle is designated by the numeral 61. The shoe is supported upon the vehicle in position so that 30 its foot 9 will make contact with suitable contact rails or ramps 62 located at different points along the trackway and insulated 35 from the track rails.

The movement of the vehicle or train may be controlled in any suitable way; but in the particular arrangement illustrated in Fig. 4, the vehicle is controlled by a suitable device 40 designated generally by the reference character K, which device is designed to control the vehicle under conditions where the vehicle should proceed cautiously. Since various devices capable of performing the necessary functions of the device K are well known in the art, and since the particular construction of the device K forms no part of this invention, it is deemed unnecessary to show and describe in detail the construction 45 and operation of the device K. The device K is illustrated as arranged to be set into operation when the electrical energy normally supplied to it is interrupted, and to be restored to its normal idle condition 50 when this electrical energy is again supplied

to it. The operation of the train control device K is controlled by a control relay 63, having three armatures 64, 65, and 66; and when the armature 66 is in its upper position, corresponding to the energized condition of the control relay 63, the device K is energized from a local source of current, as a battery 67, carried by the vehicle, along a circuit which may be traced as follows:

Circuit number one.

From the battery 67, conductor 68, device K, conductor 69, armature 66 of the control relay 63 in its upper position and conductor 70 back to the battery 67.

The armature 64 of the control relay 63 is included in a normally closed circuit for energizing said control relay from a local source of current on the vehicle, as a battery 71, when the parts of the contact shoe are in 85 their normal position, as shown; said circuit being as follows:

Circuit number two.

From the battery 71, conductors 72 and 73, 90 contact spring 74, contact bar 75 of the left-hand contact drum D, contact spring 76, conductors 77 and 78, armature 64 of the control relay 63 in its upper position, conductors 79 and 80, control relay 63, conductors 95 81, 82, and 83 back to the battery 71.

The control relay 63 is also connected to the body of the shoe, in Fig. 4, the control relay 63 being shown specifically as connected to the contacting foot 9, and to the frame or 100 wheels of the vehicle, this partial circuit for the control relay 63 being as follows:

Circuit number three.

Commencing at the wheel 61, conductors 105 84 and 80, control relay 63 and conductors 81 and 85 to the foot 9 of the shoe.

Suitable controlling circuits are provided whereby a difference of potential may be created between each ramp along the trackway and the track rails according to the traffic conditions in a certain number of blocks following that ramp; but since such controlling circuits are more complicated than is necessary to consider in this case, the 110 ramp 62 is illustrated as connected by a conductor 86 to a battery 87 which is connected by a conductor 89 to the track rail 60, a suitable switch 88 being interposed in the conductor 89, so that by opening and closing 115 said switch 88 the difference of potential generated by the battery 87 may be connected across the ramp 62 and the track rail 60, as required by traffic conditions.

In addition to the device K which automatically controls the vehicle or train, it is desirable to provide suitable proceed and caution signals on the train, these proceed and caution signals being shown in Fig. 4 as green and yellow lamps, respectively. 130

- Also, for reasons which will be made more clear hereinafter in a description of the operation, it is desirable to have a distinctive signal, designated in the drawing N. S. and hereinafter termed "the no-signals device". This no-signal device may be of any suitable construction, as for instance, a lamp of distinctive color, a movable member, or the like; and the operation of the no-signal device is controlled by an auxiliary relay, hereinafter termed the no-signal relay, which preferably has two separate windings 91 and 92 and two armatures 93 and 90, which armatures are normally in their lower position, as shown. The green lamp G and the yellow lamp Y are arranged to be controlled by the control relay 63 and the armature 90 of the no-signal relay, the circuits for said lamps being set forth hereinafter.
- 20 Operation: As the vehicle which carries the contact shoe moves along the trackway in the normal direction of traffic indicated by the arrow "X" in Fig. 4, the foot 9 of said shoe engages a ramp 62; and since the end portions of said ramp 62 slope gradually upward, the foot 9 of the shoe is swung backward in the direction opposite to the direction indicated by the arrow X and at the same time, by reason of its connection to the crank arms 13 and 13¹, is swung upward. The parallel arrangement of the crank arms 13 and 13¹ causes the under face of the foot 9 of the shoe to remain substantially parallel with the top face of the ramp as it is lifted. As the crank arms 13 and 13¹ are swung to the left, the finger 24 of the driver 23 of the lefthand crank arm 13 strikes the stop 22 of the sleeve 20 and turns said sleeve 20. The teeth 21 on the sleeve 20 communicate its movement to the corresponding lefthand lever 27, which in turn operates the lefthand contact drum D, so as to bring the contact bar 75 out of contact with the contact spring 74 and 76, thereby interrupting the circuit number two, hereinbefore traced, for normally energizing the control relay 63. During this movement of the lefthand lever 27 and the lefthand controller drum D, the righthand lever 27¹ remains stationary by reason of the fact that the finger 24¹ of the righthand driver 23¹ is carried away from the stop 22¹ of the collar 20¹ instead of into contact therewith. The movement of the lefthand lever 27 to the right telescopes the rods 32 and 33 and compresses the spring 35, so that the foot 9 of the shoe is pressed against the ramp 62 and also tends to return to its normal middle position.
- 60 Assuming that the traffic conditions are such as to permit the vehicle to proceed at unlimited speed unrestrained by the train control device K, the switch 88 will be in its closed position, so that, at the same time that circuit number two is interrupted, cur-

rent will be supplied from the battery 87 to the control relay 63 along a circuit as follows:

Circuit number four.

70 Commencing at the battery 87, conductor 89 through the switch 88 in its closed position, track rail 60, wheel 61, conductors 84 and 80, control relay 63, conductors 81 and 85, the foot 9 of the shoe, ramp 62 and conductor 86 back to the battery 87.

75 In this way, although one circuit for energizing the control relay 63 is broken when the shoe engages the ramp 62, another circuit for energizing said control relay is simultaneously established, so that the said control relay will remain energized. When the control relay 63 is energized, the green lamp G is lighted by current from the battery 71 flowing along the circuit which may be traced as follows:

Circuit number five.

80 From the battery 71, conductors 72, 94, and 108, armature 90 of the no-signal relay 63 in its lower position, conductor 109, armature 65 of the control relay 63 in its upper position, conductor 110, green lamp G and conductors 111, 103, and 83 back to the battery 71.

85 When the foot 9 of the shoe leaves contact with the ramp 62, the spring 35 returns the lever 27 to its normal position and swings the crank arms 13 and 13¹ back to their middle position, the contact drum D being simultaneously moved to reestablish the circuit number two. The parts are so proportioned that the contact drum D will return to its normal position before the foot 9 of the shoe leaves electrical contact with the ramp 62, whereby the circuit number two will be reestablished before the circuit number four is broken.

90 Assume, however, that when the vehicle passes the ramp 62, traffic conditions are such that the train control device K should be set into operation; and in this case the switch 88 should be in its open position. When the foot 9 of the shoe engages the ramp 62 and is swung and lifted, the circuit number two is broken in the same way as hereinbefore described, and since the switch 88 is open, the circuit number four is also broken, so that the control relay 63 is totally deenergized and its armatures drop. The dropping of the armature 64 of the control relay 63 opens a break in the circuit number two, so that after the foot 9 of the shoe has left contact with the ramp 62 and the contact drum D has returned to its normal position, nevertheless circuit number two will not be reestablished. The dropping of the armature 66 interrupts the circuit number one for normally energizing the device K and thereby sets the device K into

operation. The dropping of the armature 65 breaks the circuit number five for lighting the green lamp G and makes another circuit for lighting the yellow lamp Y as follows:

Circuit number six.

- From the battery 71, conductors 72, 94, and 108, armature 90 of the no-signal relay 10 in its lower position, conductor 109, armature 65 of the control relay 63 in its lower position, conductor 112, yellow lamp Y and conductor 113, 102, 103, and 83 back to the battery 71.
- 15 From the foregoing, it can be seen that by properly controlling the difference of potential between the ramps along the trackway and the track rails, the device K can be set into operation as desired, and the signals can 20 be changed from proceed to caution.

In practice, it happens that the locomotive or motor car which carries the contact shoe will sometimes move along the trackway in a direction opposite to the normal direction 25 of traffic; and in such cases the locomotive or motor car would encounter ramps between which and the track rails no difference of potential would exist, since the controlling circuits for these ramps would be affected in 30 the same way by the presence of the locomotive or motor car, even though it is moving against traffic, as they should be affected in order to protect the locomotive or motor car if it were moving in the normal direction of 35 traffic. For this reason, in order to avoid unnecessary delay to trains, it is desirable that the engagement of the shoe with a ramp should not set the train control apparatus into operation in cases where the train is 40 traveling opposite to the normal direction of traffic. In the shoe shown and described, when the vehicle carrying that shoe moves opposite to the normal direction of traffic, the crank arms 13 and 13¹ will be swung 45 backward (to the right in Fig. 4) when the foot 9 of the shoe engages a ramp. When the lefthand crank arm 13 is swung to the right the finger 24 of the driver 23 is drawn away from the stop 22, so that the lever 27 50 and the contact drum D remain stationary. In this way, when the vehicle travels opposite to the normal direction of traffic, circuit number two always remains closed and the control relay 63 will remain energized, regardless of whether or not there is a difference of potential between the ramps and the track rails.

Also, when the train travels opposite to the normal direction of traffic, it is desirable 60 to extinguish the green signal lamp G and operate the no-signal device N. S., in order that the engineer or motorman may not be deceived by the presence of a green light G.

In the practical operation of railroads, 65 moves against the normal direction of traf-

fic are generally made under special orders; and for such moves no attempt is made to provide proper signals, the responsibility being placed entirely on the engineer or motorman to obey his orders; and, in fact, the engineer or motorman must act as he should in passing over tracks which are not signaled. In order that the engineer or motorman may be constantly reminded of the fact that he has no signals to rely upon, the no-signal device is provided. In the construction shown and described, when the righthand crank arm 13¹ is swung to the right, it moves the lever 27¹ and the contact drum D¹ so as to bring the contact bar 97 80 into contact with its coöperating pair of contact springs 96 and 98, thereby closing a circuit for energizing the winding 91 of the no-signal relay as follows:

Circuit number seven.

From the battery 71, conductor 72, 94, and 95, contact spring 96, contact bar 97, contact spring 98, conductor 99, upper winding 91 of the no-signal relay and conductors 100, 101, 102, 103, and 83 back to the battery 71.

The energization of the no-signal relay raises its armature 90 and interrupts the circuits number five and number six for the green lamp G and the yellow lamp Y, and simultaneously closes a circuit for energizing the no-signal device N. S., as follows:

Circuit number eight.

From the battery 71, conductors 72, 94, 100 and 108, armature 90 of the no-signal relay in its upper position, conductor 114, no-signal device N. S. and conductors 115, 107, 101, 102, 103, and 83 back to the battery 71.

Also, when the no-signal relay is energized, its armature 93 is raised to close a circuit for maintaining its lower winding 92, energized, said maintaining circuit being as follows:

Circuit number nine.

From the battery 71, conductors 72, 73, contact spring 74, contact bar 75, contact spring 76, conductors 77 and 104, armature 93 in its upper position, conductor 105, lower winding 92 of the no-signal relay, and conductors 106, 107, 101, 102, 103, and 83 back to the battery 71.

When the foot 9 of the shoe leaves engagement with the ramp, the contact drum D¹ 120 will be restored to its normal position to break the circuit number seven for energizing the upper winding 91 of the no-signal relay; but the lower winding 92 of said relay being energized, its armatures 90 and 93 will 125 remain in their upper position. The lower winding 92 of the no-signal relay will be de-energized when the train changes its direction of movement and passes the first ramp 62 going in the normal direction of traffic, 130

since this will cause the foot 9 of the shoe to be moved to the left to move the contact drum D and break the maintaining circuit number nine at the contact springs 74 5 and 76.

The foot 9 of the shoe is revolubly mounted in the supporting block 8 so that said foot in engaging a ramp at one side of the axis on which said foot may rotate will 10 be rotated with a scraping action which will insure a better electrical contact and which will free the surface of the ramp from sleet, snow, and the like. If desired, an emergency shoe or plunger may be combined with the 15 construction of the shoe shown and hereinbefore described with very little change, such an emergency shoe being shown and described in my prior application Serial No. 44,497 filed Aug. 9, 1915. Also, al- 20 though one form of a train control system and controlling circuits therefor has been illustrated in Fig. 4, it is to be understood that Fig. 4 merely shows an illustrative application of the contact shoe, and that said 25 shoe is not limited to this application. Only one contact drum and its associated operating mechanism may be used, providing it is desired to dispense with the no-signal device. Other circuits than these shown may 30 be controlled by the contact drums D and D¹ and either opened or closed by the movements of said contact drums at predetermined times.

Although I have particularly described 35 the construction of one physical embodiment of my invention, and explained the operation and principle thereof, nevertheless, I desire to have it understood that the form selected is merely illustrative, but does not 40 exhaust the possible physical embodiments of the idea of means underlying my invention.

What I claim as new and desire to secure by Letters Patent of the United States, is:

45 1. A contact shoe for automatic train control systems comprising parallel crank arms pivotally supported at their upper ends, a member pivotally connected to the lower ends of said crank arms, and a circuit controlling device operated by said crank arms.

50 2. A contact shoe for automatic train control systems comprising a body portion, a revoluble foot movably mounted on said body portion and adapted to swing in either direction from a middle position, and circuit controllers operatively connected to said shoe and selectively operated thereby by its movements in either direction.

55 3. A contact shoe for automatic train control systems comprising a conducting member adapted to be attached to a railway vehicle and mounted on parallel supporting arms to swing in either direction lengthwise of the vehicle from a middle position, a cir- 60 cuit controlling device operatively connected

to said member and operated by the swinging movement thereof to control different circuits selectively, and means for restoring said member to its normal middle position.

4. A contact shoe for automatic train control systems comprising a conducting member mounted to move in either direction from a middle position, and two movable circuit controlling devices operated selectively and separately by the movements of said member in opposite directions. 70

5. A contact shoe for automatic train control systems comprising a body portion, a foot supported from said body portion by two parallel crank arms pivotally connected thereto and to said body portion, a circuit controller operated by each of said crank arms, means for yieldingly holding said crank arms in their normal positions, and means for operatively connecting each of 80 said crank arms with its corresponding circuit controller to cause said circuit controller to be moved when said crank arm is moved in one direction, and to permit said circuit controller to remain in its normal 85 position when said crank arm is moved in the opposite direction. 90

6. A contact shoe for automatic train control systems comprising a body portion, parallel crank arms pivotally connected to said body portion, a block pivotally connected to said crank arms, a contact disk revolubly mounted in said block, and a circuit controller operatively connected to said crank arms. 95

7. A contact shoe for automatic train control systems comprising a body portion, parallel crank arms pivotally connected to said body portion and extending downwardly therefrom, a block pivotally connecting said 105 crank arms at their lower ends, a contact disk having a bearing stud journaled in said block, said bearing stud having a circumferential groove therein, a pin extending through said block and said groove to fasten 110 the contact disk in place, and circuit controlling means operatively connected to said crank arms.

8. A contact shoe for automatic train control systems comprising a foot, parallel crank arms pivotally supported at one end and pivotally connected at the other end to said foot, levers operated selectively from a normal position by the movement of said crank arms in opposite directions, separate 120 circuit controlling devices operated by said levers, and means for restoring said levers to their normal position.

9. A contact shoe for automatic train control systems comprising parallel crank 125 arms each pivotally supported at one end, a block pivotally connected to the other ends of said crank arms, and a conducting foot removably secured to said block.

10. A contact shoe for automatic train 130

- control systems comprising a body portion having an inclosed casing, an oscillatory contact carrying drum supported in said casing, a conducting member carried by said body portion and adapted to swing in either direction from a middle position, and means operatively connecting said member and said drum, said means causing movement of said drum when said member is 5 swung in one direction and permitting swinging movement of said member in the opposite direction independently of said drum.
- 10 11. A contact shoe for automatic train control systems comprising parallel crank arms pivotally supported at their upper ends, a member pivotally connecting the lower ends of said crank arms, and separate circuit controlling devices adapted to be 15 operated alternately by the swinging movement of said crank arms in opposite directions.
12. A contact shoe for automatic train control systems comprising parallel crank arms pivotally supported in their upper ends, a member pivotally connecting the lower ends of said crank arms, and means 20 tending to maintain said crank arms in the middle position.
13. A contact shoe for automatic train control systems adapted to be attached to a railway vehicle and comprising a circuit controlling device, a lever for operating said 25
- device and biased to a predetermined normal position, a movable member mounted to swing in opposite directions in accordance with the direction of travel of the vehicle, and means connecting said member and said lever for causing movement of the lever only when the member is moved 30 in one direction.
14. A contact shoe for automatic train control systems comprising a casing fastened to a bar of insulating material adapted to be attached to a railway vehicle, parallel crank arms supported by said casing, a contacting foot connected to said crank arms, and separate circuit controlling devices operatively connected to said crank arms and operated selectively in accordance 35 with the direction of movement of said crank arms.
15. A contact shoe for automatic train control systems comprising a body portion adapted to be attached to a railway vehicle and insulated therefrom, downwardly extending crank arms supported by said body portion to swing on a horizontal axis, a contacting foot pivotally connected to said crank arms, a circuit controller, a lever for operating said circuit controller, and means interconnecting said lever and a crank arm 40 for causing movement of the lever only when the crank arm is moved in one direction.
